[57] CLAIM

The ornamental design for a stanchion for a beverage tap, as shown and described.

DESCRIPTION

FIG. 1 is a side elevational view of a stanchion for a beverage tap showing my new design, the undisclosed sides are similar in appearance except for the omission of the rectangular shaped opening in the bottom wall; FIG. 2 is a cross-sectional view thereof taken on line 2—2 of FIG. 1;

FIG. 3 is a cross-sectional view thereof taken on line 3—3 of FIG. 1;

FIG. 4 is a top plan view thereof; and

FIG. 5 is a bottom plan view thereof;

FIG. 1.

Fig. 4.

Fig. 5.
